UNITED STATES PATENT OFFICE.

ARTHUR H. BOETTCHER, OF CHICAGO, ILLINOIS, ASSIGNOR TO STROMBERG MOTOR
DEVICES COMPANY, OF CHICAGO, ILLINOIS, A CORPORATION OF ILLINOIS.

CARBURETER.

1,173,246.

Specification of Letters Patent. Patented Feb. 29, 1916.

Application filed January 29, 1912. Serial No. 673,983.

To all whom it may concern:

Be it known that I, ARTHUR H. BOETTCHER, a citizen of the United States, residing at Chicago, in the county of Cook 5 and State of Illinois, have invented new and useful Improvements in Carbureters, of which the following is a full, clear, concise, and exact description, reference being had to the accompanying drawings, forming 10 a part of this specification.

My invention relates to charge forming devices for internal combustion engines and has to do with that type of carbureter designated in the art as "multiple feed", the idea 15 being to vary the amount of fuel and air supplied in accordance with the demand made by the associated engine. This regulation is secured by the use of a valve which simultaneously varies the amount of air admitted and cuts in or out a corresponding 20 number of the plurality of fuel supply devices provided. It will appear that, broadly, so far as the features of my invention are concerned, this valve may be operated manually or may be operated automatically by means of a governor connected 25 with the engine or by means of the suction of the engine.

In the specific form of my invention here- 30 in shown and described, the valve is operated by the suction of the engine and in this way its workings are a matter of its response to the requirements of the engine. In devices of this kind it is old in the art 35 to provide an air inlet, a plurality of fuel jets, and a valve for simultaneously varying the size of the air inlet and the number of open fuel jets. The valve, in this particular instance, is in the form of a piston, 40 the chamber on one side of the valve being connected with the manifold of the engine. By the movement of this valve, the space connected with the engine may be made greater or smaller, in accordance with the 45 demand of the engine, and simultaneously more or fewer of the gasoline inlets or jets, which are properly arranged along the line of travel of the valve, are open to the draft of air entering the carbureting chamber. 50 These devices have been found to be effective and, so far as the movement of the valve is concerned, sensitively responsive to the demand made by the engine. However, in the devices of the prior art the changes 55 in the size of the air inlet were infinitely

small while the amount of fuel increased step by step. That is, since there was a single air inlet and a plurality of fuel jets, and no arrangement to overcome the difficulty, the amount of air admitted could be 60 increased to some extent without correspondingly increasing the amount of fuel, since the slightest movement of the valve would vary the amount of air but a considerable movement thereof would be required to 65 open or close another fuel inlet, or render ineffective another fuel inlet. The valve could move the entire distance between the inlets to increase the amount of air without opening the next succeeding inlet. 70

It is the object of my invention to overcome this difficulty and to provide a carbureter of the type referred to wherein the slightest movement of the valve to increase the amount of air would result in a corresponding increase in the amount of fuel. Thus every part of the movement of the valve, however slight, to increase the air inlet, will be accompanied by an increase in the amount of fuel admitted, and every 80 movement of the valve to decrease the amount of air, however slight, will be accompanied by a decrease in the admission of fuel. So long as this operation can take place, the desired definite proportions between the air and fuel are maintained, but with the step by step system the undesirable variations in the proportion can not be avoided. I am aware that attempts have 85 been made to vary the size of a single fuel inlet, when the air inlet is varied but these have not been found to be successful since the control is difficult if not impossible and the range is so limited. 90

In order to secure the objects of my invention as set forth in the preceding paragraph, I provide a special form of valve which operates to positively open and close the fuel jets and also to restrict some of them. As before stated, the valve of my invention is 100 in the form of a piston, and the cylinder in which it operates is provided with a longitudinally extending air inlet and a longitudinal row of fuel inlets. The valve operates to connect more or less of this air inlet with the carbureting chamber and also positively and correspondingly opens and closes the fuel jets. In view of the fact that it is the prime object of the device to maintain a 105 definite proportion between the air and fuel, 110

this operation is highly important since at no time can the fuel be drawn from any of the jets unintentionally. I secure this desirable feature by means of a simple and inexpensive structure and the fact that some of the fuel inlets are allowed to respond partially to the suction of the engine avoids any tendency for the leaking or by-passing of fuel around the valve in response to any unbalanced vacuum. Thus, the unintentional passage of fuel, which would upset the constituent proportions of the combustible mixture, is prevented and only those fuel jets which are intended to operate will respond. In this way the device is always sensitive and accurate and maintains the proper constituent proportions of the combustible mixture whatever be the speed of the engine.

20 My invention is embodied in the device illustrated in the accompanying drawings, in which—

25 Figure 1 is a longitudinal sectional view taken on an axial plane through my device, Fig. 2 is a cross-sectional view taken on the plane of the line 4—4 of Fig. 1 and looking in the direction indicated by the arrows.

30 Like reference characters are applied to the same parts throughout the several views.

The main framework of the carburetor itself is in the form of a generally cylindrical body 10 which provides the carbureting chamber 11, a sensitive piston cylinder 12, 35 and a valve piston cylinder 13, the cylinders extending in opposite directions from the carbureting chamber and being in axial alignment therewith and with each other. The carbureting chamber 11 has the upwardly extending outlet pipe 14 which is provided with a flange 15 to facilitate its attachment to the piping which leads to the engine. A rock shaft 16 extends diametrically across the outlet pipe 14 and carries 40 the throttle valve 18. The shaft 16 extends beyond its bearings in the pipe 14 and is there provided with an operating lever rigidly mounted thereon. If the engine with which the carburetor is associated is mounted 45 as a car motor, this lever is connected by means of suitable linkages conveniently located on the dash of the automobile.

The sensitive piston chamber 12, in the specific embodiment herein shown, is separated from the carbureting chamber 11 by means of a wall 25 which has an aperture 26 providing for pneumatic connection between the carbureting chamber and its cylinder. The wall 25 carries an elongated boss 60 27 which has a longitudinal bore in axial alignment with the cylinders 12 and 13. A rod 28 is mounted to slide with a bearing fit in this boss, as best illustrated in Fig. 1, this rod being of such length that it may 65 extend into both cylinders 12 and 13. With-

in the cylinder 12 the rod 28 is provided with a piston 29. A spiral spring 30 is disposed between the piston 29 and the wall 25. The cylinder 12 is provided with a cover 31 which is provided with an opening 32 to the atmosphere. The spring 30 tends to move the piston 29 to the left (Fig. 1) and a screw 33, in the cover, limits the normal position of this piston. The other end of the rod 28 is provided with a piston 34 which is the valve hereinbefore referred to and herein-after to be described specifically. In order to distinguish conveniently between the two pistons I shall refer to the piston 29 as the "sensitive" piston and to the piston 34 as the valve. It will be understood, of course, that the suction of the engine has some effect on the valve 34 and it will be noted that the valve 34 and the piston 29 are of different diameters so as to secure a "differential" action, the difference in the areas of the two parts being that which makes possible the effective operation.

It will be seen from the drawings that the cylinder 13 is supplemented by a downwardly extending box or passage 36 which is substituted for substantially one-fourth of the peripheral area of the cylinder. The interior of this box connects directly with the interior of the cylinder and is exposed at the bottom directly to the atmosphere as indicated at 37. This is the air inlet.

It will be seen that, for the greater part of the periphery of the valve 34, there is a suitable space between it and the inside surface of the cylinder. A shell or sleeve 38, as best shown in Figs. 1 and 2, occupies this space, fitting snugly within the cylinder and extending the entire length thereof. It will be noted that the sleeve 38 is not a complete cylinder, but has what may be termed an opening 40 which is approximately the same size as the opening between the box 36 and the cylinder 13. The valve 34 is therefore cut out to accommodate the sleeve 38 as far around its periphery as need be, while the remaining part of the piston is of a radius equal to the inside radius of the cylinder, as is the outer radius of the sleeve. The sleeve 38 carries a head 39 which fits in a pocket 110 at the end of the casing and which closes the end of the cylinder 13. It will be seen from Fig. 2 that by turning the sleeve the size of the air inlet can be decreased.

Within the box 36 a fuel nozzle block 44 is held in an upright position so that the valve 34 may ride in positive sliding contact upon the top thereof. This block is substantially rectangular in shape and is disposed directly below the axis of the cylinder 13, the axes of the block lying in the same plane therewith. The essential feature is at the top of the block, where the fuel jets are, as will be explained, and this top is tangent to the surface of the valve 34 or better than 130

that, slightly concave to fit the convex surface of the valve. The block 44 is mounted upon lugs 45, 45 extending inwardly from the wall of the box 36 and from the removable cover 46, held in place by the screws 47, 47, which permits of ready access to the interior of the box. The box 36, as shown in Fig. 2, is of such size and disposition that there is considerable space for the passage 5 of air on both sides of the nozzle block.

10 The nozzle block is provided with a plurality of vertical passageways 48, 48 and the tops of these passageways are restricted by means of the plate 49 upon which the valve 34 slides, this plate having alining 15 apertures 50, 50, which form the fuel jets. Theoretically, it would be proper to have the valve 34 be of such width that it could cover all and positively close all the jets or 20 nozzles at the same time. Practically, however, this is not necessary and the valve 34 may be reduced in width, quite as shown in the drawings, so as to economize in metal and reduce the over-all dimension of the 25 device, since those nozzles which are uncovered to the right of the valve (Fig. 1) are so remote from the aspiration and suction effects as limited by the position of the valve that they will not respond. The position 30 of the piston 34 determines the size of the active zone, that is, the zone subject to the suction of the engine. As will be described presently, the first one, two or three nozzles 50 are exposed to this active zone. 35 The next three, four or five, or probably more, remote from the carbureting chamber, are positively closed by the valve 34 while the remaining ones remote from the carbureting chamber are as much inactive as 40 those positively closed because they are so far removed from the active zone, the zone to the right of the valve (Fig. 1) being inactive or "dead."

45 It will be seen that the main part of the valve 34 fits down tightly upon the top of the nozzle block while a limited front part 51 tapers or converges toward the carbureting chamber to leave a tapered space between that part of the piston and the top 50 of the nozzle block as illustrated in Fig. 1. In the drawings it has been necessary to exaggerate this taper somewhat in order that the illustration might be clear. It will be seen that with this construction of valve 55 the main part of that member positively closes three, four or five or some other convenient number of nozzles while the tapered edge of the valve merely restricts the next one, two or three nozzles, toward the carbureting chamber, the 60 nearest of these toward the carbureting chamber being the least restricted. Beyond that, toward the carbureting chamber, the nozzles are free and open. It will thus be 65 seen that I provide an arrangement whereby

there are first wide open nozzles, second, restricted nozzles, or a series of increasingly restricted nozzles, and third, positively closed nozzles. Regardless of the position of the valve there will always be these three sets of nozzles. It will be seen that as the valve 34 moves to the right (Fig. 1), any restricted nozzle will gradually become less and less restricted, by reason of the gradually enlarging passageway at that point, 75 due to the tapered part of the valve, until finally it is entirely exposed to the aspiration and suction effects. Similarly, a closed nozzle is not immediately exposed to the active zone but it is gradually opened 80 by the tapered part of the valve. Thus, however slight may be the movement of the valve there is a corresponding and proportioned change in the amount of fuel passing by it. Since it is only the left hand side of 85 the valve (Fig. 1) which is exposed to the active zone, the volume of air passing through the box 36 and into the carbureting chamber is gradually changed, one way or the other, by means of the valve. There 90 again, the slightest movement of the valve results in an increase in the amount of passing air and in this way I maintain a constant proportion between the constituents 95 of the combustible mixture. In the case of the fuel as in the case of the air the variations are infinitely small, this being made possible by the oblique valve face. The operation is positive and reliable and sensitively accurate because the fuel nozzles are 100 positively opened and closed and the position of the valve always determines exactly those nozzles from which there is to be a response. Since there is a response from the 105 restricted nozzles, the suction and aspiration effects which might tend to draw around the main part of the piston, unless the pressures are otherwise balanced, are satisfied in that way and there will be no 110 leaking from the nozzles which are intended to be positively closed. In the drawing, the valve is shown in the starting position and it will be seen that two of the nozzles are wide open, three are increasingly restricted, and the succeeding ones are 115 positively closed.

120 The passageways 48, 48, which are vertical and parallel, are all connected together at the bottom by means of a horizontal passage 52 which is alined with a passageway 53 in the wall of the box 36. This passageway communicates with a float chamber 54 which is closed at the bottom by means of a base piece 55 to which a pipe 56, leading from the fuel supply, is connected. The base piece is provided with a valve seat 57 with which a valve 58 is associated. This valve, through the intervention of lever mechanism 59, 59 is operatively connected 125 with a float 60. In this way the fuel is 130

maintained at a definite height in the float chamber and in the fuel passageways 48, 48.

I claim as new and desire to secure by Letters Patent:

- 5 1. In a carbureter, a carbureting chamber, an air inlet therefor, a plurality of fuel inlets therefor and a single tapered valve for simultaneously determining the size of said air inlet and progressively increasing 55 increasingly restricting a series of said fuel inlets and positively closing others.
- 10 2. In a carbureter, a carbureting chamber, an air inlet therefor, a plurality of fuel inlets therefor and a single tapered valve responsive to the suction of the engine for simultaneously determining the size of said air inlet and progressively increasing 60 increasingly restricting a series of said fuel inlets and positively closing others.
- 15 3. In a carbureter, a carbureting chamber, an air inlet therefor, a plurality of fuel nozzles therefor, a single tapered valve for simultaneously determining the size of said air inlet and progressively restricting some 65 of said fuel nozzles and positively closing others, and a piston responsive to the suction of the engine mechanically connected with said valve.
- 20 4. In a carbureter, a carbureting chamber, an air inlet therefor, a row of fuel nozzles terminating in a single plane, and a single tapered valve sliding upon said fuel nozzles for progressively positively closing some of said nozzles and restricting others 70 and determining the size of the air inlet.
- 25 5. In a carbureter, a carbureting chamber, an air inlet therefor, a row of fuel nozzles terminating in a single plane, and a single tapered valve sliding upon said fuel nozzles for progressively positively closing some of said nozzles and determining the size of the air inlet, said valve having a part 75 restricting other fuel nozzles.
- 30 6. In a carbureter, a carbureting chamber, a cylindrical valve chamber connected therewith, an air opening extending substantially the length of said valve chamber, a fuel nozzle block arranged in said air opening, and a piston valve mounted in said 80 valve chamber and sliding upon the top of

said nozzle block to positively close some of the nozzles, the part of said piston toward the carbureting chamber being tapered to diminishingly restrict the adjoining fuel nozzles, said piston valve also determining the part of the air opening in communication with the carbureting chamber.

7. In a carbureter, a carbureting chamber, a cylindrical valve chamber connected therewith, an air opening extending substantially the length of said valve chamber, a fuel nozzle block arranged in said air opening, a piston valve mounted in said valve chamber and sliding upon the top of said nozzle block to positively close some of the nozzles, the part of said piston toward the carbureting chamber being tapered to diminishingly restrict the adjoining fuel nozzles, said piston valve also determining the part of the air opening in communication with the carbureting chamber, a second and larger cylinder in alinement with said valve chamber, and a piston in said cylinder mechanically connected with said piston valve to form a sliding structure responsive to suc-

tion.

8. In a carbureter, a carbureting chamber, a cylindrical valve chamber connected therewith, an air opening extending substantially the length of said valve chamber, a fuel nozzle block arranged in said air opening, a piston valve mounted in said valve chamber and sliding upon the top of said nozzle block to positively close some of the nozzles, the part of said piston toward the carbureting chamber being tapered to diminishingly restrict the adjoining fuel nozzles, said piston valve also determining the part of the air opening in communication with the carbureting chamber, and a manually operated sleeve valve partly surrounding said piston valve for varying the other dimension of the air inlet.

In witness whereof, I hereunto subscribe my name this 26th day of January, A. D. 1912.

ARTHUR H. BOETTCHER.
